T. WOODS

WRENCH FOR USE IN RESTRICTED LOCATIONS

Filed Jan. 27, 1926

FIG. 2

FIG. 1

FIG. 3

Inventor
Theodore Woods
Attorney
Thomasson

UNITED STATES PATENT OFFICE.

THEODORE WOODS, OF WEST LINN, OREGON.

WRENCH FOR USE IN RESTRICTED LOCATIONS.

Application filed January 27, 1926. Serial No. 84,080.

The object of my invention is for the placing of threaded nuts upon bolts in highly restricted locations, wherein it is necessary for the wrench to maintain the nut to be placed upon the bolt within the head of the wrench and when so located to thread the same upon the bolt by the turning of the head without the movement of the handle member of the wrench.

10 An additional object of my invention consists in having a closure plate disposed upon one side of the wrench head, which may be removed and snapped into position upon the opposite side of the head, thus making either 15 side of the head of the wrench adaptable for the retention of the nut therein.

With these and incidental objects in view, the invention consists in certain novel features, of construction and combination of 20 parts, the essential elements of which are set forth in the appended claims, and a preferred form of embodiment of which is hereinafter shown with reference to the drawings which accompany and form a part of this 25 specification:

In the drawings:—

Fig. 1 is a perspective view of the wrench, partially in section at the head end.

Fig. 2 is a cross section view, showing 20 part of the body portion broken away to better illustrate my device.

Fig. 3 is an end view, taken on line 3—3 of Fig. 2, looking in the direction indicated.

Like reference characters refer to like 25 parts throughout the several views.

The body portion and handle member of the frame is preferably made of two parts 1 and 2, the same being fastened together by suitable fastening means, as rivets 3. The 30 head 4, of the wrench is formed at an angle to the handle section and has disposed therein the revoluble socket jaws 5, having an inner face 6, adapted to fit about the nuts and held therein. I have shown the head to be 35 hexagonal in form, but do not wish to be limited to a hexagonal form. Disposed about the outer periphery of the member 5, is formed a gear 7, the said gear being passed between the two framed members which are 40 spaced apart sufficiently to maintain the same in position therein. Running longitudinally of the body portion parallel thereto is a drive shaft 8, held within suitable bearing upon the member 2, and having a 45 knurled operating disk 9, secured thereto at one end and having a beveled gear 10, mount-

ed upon the other end which engages with the gear 7. A closure plate 11, fits upon the annular head of the wrench, by means of the projections 12, projecting from one side 60 thereof and which detachably engage the head 4, the object of which is to form a pocket within the socket jaws of the wrench, to prevent the falling out, or the pushing out of the nut from the same when it engages 65 with the bolt upon which it is to be threaded, the closure plate may be removed from the side shown and placed upon the opposite side of the head section. An additional wrench socket 13, may be formed upon the 70 opposite end of the wrench.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims 75 which follow.

What I claim is:

1. A wrench, comprising a body portion composed of two parallel members secured together, there being an annular enlargement formed at one end, said annular enlargement being at an angle to the main body portion, and said parallel members being spaced apart at said annular enlargement, socket jaws revolubly maintained in said annular enlargement, a gear formed upon said socket jaws, a drive shaft mounted to one side of said body portion and parallel thereto, an operating disk mounted at one end of said shaft, and a bevel gear mounted at the other end of said shaft and engaging 95 with the gear mounted about the revoluble jaws.

2. A wrench, comprising a body portion composed of two parallel members secured together, and there being an annular enlargement formed in one end of said body portion, said annular enlargement being at an angle to the main body portion, and said parallel members being spaced apart at said annular enlargement, socket jaws revolubly 100 maintained in said annular enlargement, a gear formed about said socket jaws, a drive shaft mounted to one side of said body portion and parallel thereto, an operating disk mounted at one end of said shaft a bevel 105 gear mounted at the opposite end of said shaft and engaging with the gear mounted 110

about the revoluble jaws, and a reversable closure adapted to removable attachment to the opposite sides of said annular enlargement.

5 3. A wrench comprising two parallel members secured together to form a body portion and terminating in an annular enlargement at one end, said members being spaced apart at the point of said annular 10 enlargement, said annular enlargement being formed at an angle to said body portion; socket jaws revolvably maintained in said annular enlargement and between said spaced

parallel members; a gear formed upon said socket jaws; a drive shaft mounted at one side of said body portion and parallel thereto; an operating disk mounted upon one end of said shaft, a bevel gear mounted upon the other end of said shaft and engaging the gear formed upon the socket 15 jaws; a removable closure, and means on said removable closure permitting the same to be removably mounted to either side of said annular enlargement.

THEODORE WOODS.
